UNITED STATES PATENT OFFICE.

JOHN THOMSON, OF NEW YORK, N. Y., ASSIGNOR TO JOHN THOMSON PRESS COMPANY,
OF JERSEY CITY, NEW JERSEY, A CORPORATION OF NEW JERSEY.

ELECTRIC ZINC-DISTILLING FURNACE AND CONDENSER FOR PRODUCING BLUE POWDER.

1,214,842.

Specification of Letters Patent.

Patented Feb. 6, 1917.

Application filed January 28, 1916. Serial No. 74,828.

To all whom it may concern:

Be it known that I, JOHN THOMSON, a citizen of the United States, and a resident of the borough of Manhattan, city of New York, county and State of New York, have invented certain new and useful Improvements in Electric Zinc-Distilling Furnaces and Condensers for Producing Blue Powder, of which the following is a specification, 10 reference being made to the accompanying drawings, forming a part thereof.

This invention relates to the metallurgy of zinc having particular reference to the purification of impure spelter by distillation in an electric furnace and then condensing, or precipitating, the fume in the form of "blue-powder" or dust, and the objects are to increase the purity and effectiveness of the said material at a minimum cost of production.

The accompanying drawings represent a preferred mode of realizing the ends in view, but it will be understood that the invention is not necessarily confined to the 25 precise details shown therein. In said drawings,

Figure 1 is a vertical, transverse center section of the furnace and its condenser, of which two are shown in duplicate, as on the 30 line A of Fig. 2.

Fig. 2 is a half vertical longitudinal center section of the furnace, on its left hand side, as on the line B of Fig. 1, while its right hand side is an elevation.

Fig. 3 is a plan view on the plane C of Fig. 2, the forward condenser being shown in horizontal section.

Fig. 4 is a part longitudinal section of the condenser, as on the line D of Fig. 1.

Fig. 5 is an enlarged, detached front elevation of a plate forming a part of the condenser; and

Fig. 6 is a half end elevation and transverse section of said plate.

The heating system of the furnace is comprised in a carbon resistor, E, formed of two slotted plates, 7, 8, producing a zig-zag electric circuit, attached by a connector, 9, to operate in series by electrification from 45 right and left hand terminals, 10, 11.

Beneath the resistor is a shallow trough or open tank, 12, which contains the bath of molten spelter, 13, supplied by a spout, 14, located in an end-wall of the furnace.

As the rising velocity of the fume from the bath toward the resistor is comparatively slow it becomes more or less super-heated. In order to eliminate some portion of this super-heat and yet to prevent a free upward escape of heat from the resistor itself, an overlying compound septum is provided, consisting of a lower series of refractory plates, 15, in the ends of which are formed a plurality of ports, 16, that is two series of end ports are disposed along the right and left hand sides of the furnace chamber. Above this lower series of plates is another series, 17, which also have a plurality of ports, 18; but these are formed in their centers and lie along the longitudinal line B. In this wise there are produced a primary or resistor chamber, H, an intermediary septum chamber, I, and an upper or fume chamber, J. The consequence of this arrangement is that the fume passes up through the end ports, 16, of the lower septum, deflects left and right flowing horizontally across the septum chamber, head-on as indicated by arrows a, rises through the center ports, 18, of the upper septum, as indicated by arrows b, and thence makes a direct impingement against the cover, L, as denoted by arrows, c. The cover consists of several relatively thin refractory tiles or carbon slabs, 19, upon which free bricks, as 20, may readily be stacked, or removed, to cause a more or less free or a restricted radiation of heat. The particular objects of the ported septums are to conserve heat in the resistor chamber, H; to produce a considerable diminution in the temperature of the fume immediately it leaves the upper ports and to thence effect a very perfect volumetric division and a right and left hand deflection thereof, across chamber, J, as indicated by arrows d, e.

Contrary to the supposition generally entertained by zinc specialists, or "experts," the problem of condensing, or precipitating all, or essentially all, of the fume which can be evolved in a furnace unit in the form of "blue-powder" presents many difficulties. The bulk of blue-powder, or zinc-dust, hitherto used in the arts has been a by-product, a residuum of fume not condensed as fluid metal, which is considerably oxidized (hence the term "blue") and frequently contains coalesced metal in the form of visible

spheres. Excessive oxidization is objectionable as it reduces the purity of the dust. Excessive oxidization also leads to "shotty" dust which is objectionable as it may require screening.

When blue-powder is produced in a high state of perfection, it is in fact a "dust" of a fineness of subdivision to which the term "impalpable" is properly applicable; it may assay, in zinc, upward of 96 percentum and, as to its color, gray would more fittingly apply than blue.

While the foregoing statements, as also others to follow, are more or less academic in character, they are here introduced with the view of possibly making the context clearer. A given volume of pure zinc-fume, that is fume not associated with vaporized lead, cadmium, mercury, etc., will be precipitated as gray-dust if, firstly, it does not come in contact with a heated surface whose temperature may range between 420° and 930° C.; if, secondly, there is not sufficient air present to form ZnO and if, thirdly, it is relatively suddenly chilled at temperatures ranging from, say 400° C. downwardly. Again referring to the drawings, an effect of causing a given volume of fume to split, as it were, in the center of the upper chamber and flow right and left, according to arrows *d*, *e* is to reduce the lineal velocity of flow by 50 percentum as compared to the velocity of flow of the same volume when flowing across the chamber in one direction only.

The upper chamber has no sides, except as relates to a series of short, narrow pillars 21, 22, which serve to support the roof-plates; hence, the intervening spaces 23, 24 are virtually extensions of the chamber and present a flow-area effectively equal thereto. The object thereof is to introduce the fume to the condensers, M, N, at the least possible velocity; in the greatest possible volume and at the utmost uniformity of temperature.

The condensers extend upwardly from and along the side walls of the furnace and are preferably constructed from plates of graphitized carbon, 25, forming relatively narrow but high and long horizontal rectangular chambers, R, S, in fact their lengths are equal to that of the upper furnace chamber. These plates are excellent conductors of heat and, for some reason not fully known, there appears to be a lesser tendency for zinc-dust to adhere thereto than to other available materials. Then, too, graphitized carbon may be readily machined. Each plate is arranged to be water-cooled by means of copper or brass coils, 26, as shown in Figs 1, 5 and 6, this being very effectively accomplished by milling a series, usually four, of parallel lengthwise grooves, 27, in one of the side surfaces. The coil is then laid in the grooves and any free space is

tightly packed with a paste chiefly formed of powdered graphite, as 28, Fig. 6.

The consequence is that the entire outer surface of the tubing is brought into intimate physical contact with the plate, whereby the transfer of heat is uniquely effective. The flow of water through each coil is denoted by arrows *t*. The cooling water may be caused to circulate through each plate as a distinct unit, or any two or all of the plates may be coupled, as indicated in dotted outline, 29, when the water is caused to circulate in series.

It will now be perceived that immediately the hot fume passes beyond the outer edges of the pillars, 21, 22, it is in free space and its first impingement, at very low velocity and upon a large surface, viz., upon the vertical surface of the lower, outer plates as denoted by arrows *x*, *y*, thence reacting and flowing in a natural upward direction, as arrows *r*, *s*, more or less filling, according to the amount of prior condensation, the upper reaches of the condensing chambers. Any hydrous or other gases may be burned at the vents 30.

The chilled fume, as a dust, 31, Fig. 1, precipitates and is collected at the bottom upon declined surfaces, 32, 33. Between the lower edge of the lower outer plates and the aforesaid declines are free slit-like spaces 34, 35, normally closed by sharp-edged steel plates, acting as valves, 36, 37, secured against the outer surfaces of the plates by clips, 38, 39, and having end-handles, as 40, 41. Whenever a sufficient quantity of dust will have been collected, a valve is raised and the dust is then free to run out. When the rapidity of the flow of dust indicates that the charge is about exhausted, the valve is practically instantly closed; the flowing stream is shut off by a vertically movable valve and no air can enter the chamber. If for any cause the dust does not run freely, it can readily be released by poking. As the valve is not contained within the chambers, it is not liable to become stuck or wedged, or if so a clearance can readily be effected, yet in no instance will there be danger of a back-flow of air with the consequent possibility of an explosion.

Another reason for introducing the fume to the condensers at a low rate of flow and thereafter providing upper chamber spaces of large volumetric capacity, is that the most minute particles of the dust are so nearly molecular in character that they will float like smoke. Consequently, it is not only essential to diminish the entering velocity to the utmost extent; but to provide an ample period of time for precipitation out of the cloud of fume.

The side and end plates may be securely bound together by means of clamps or screws; but the top plates are preferably left

free so that, in the event of an explosion, they will blow off. Also, in this wise, either of the condensers can be put out of operation by inserting bricks, or a slab, to stop the flow 5 of fume from the furnace.

The precipitating capacity of a chamber of given volume may be substantially increased by inserting therein a series of spaced plates, 42, conveniently suspended 10 upon a rod 43, as shown at the left hand side of Fig. 1 and in the detail view, Fig. 4; which serve both to augment the impinging surface and the heat conduction.

As previously intimated, the chilling temperature of the interior surfaces of the condensers must be below the melting point of zinc, or say not higher than about 400° C. and it may be to any extent lower than that except when hydrous vapor is contained in 15 or with the fume. In such circumstance, the temperature should not be low enough to condense such vapor, or steam, to water which would mix with and produce objectionable caking of the dust. This condition, 20 however, is only likely to exist when a furnace is first put into operation and during 25 the drying out interim.

It is to be observed that the lower surfaces 30 of the spaces containing the supporting pillars are sloped downwardly, and inwardly, as 44, whereby should any fume be condensed thereat to liquid metal it will not run into the condensers, where it would mix with the dust, but back into the furnace and 35 thence through the septum plates to the trough to be again distilled.

By this system of distilling there is rendered possible the obtaining of a pure zinc-fume which is nearly if not entirely isolated 40 from other carrying gases; a pre-cooling of the fume within the furnace and delivering it at a low entering velocity to the condensers; a complete temperature control of the condensers and a complete exclusion of air 45 from within the furnace and condensers. The resulting product is of the highest possible purity and possesses a range and possibility of use, as in the manufacture of anilin dyes, for cyaniding and sherardizing, 50 not otherwise attainable. Moreover,

under the foregoing conditions, the resistor-element may be run up to higher temperatures than would be permissible in other circumstances, thereby sensibly increasing the thermal efficiency of the furnace.

55

The improvements herein set forth are not limited to the precise construction and arrangement shown and described for they may be embodied in various forms and modifications without departing from the 60 spirit and scope of the invention.

What I claim is:

1. In an electric furnace for distilling fusible metals by means of a radiating resistor suspended above a bath, a compound 65 septum formed of plates suspended above the resistor, the lower series being provided with a plurality of end ports while the upper series is provided with a plurality of center ports, whereby the fume will first 70 pass upwardly, next in a head-on direction between the two series of septum plates, thence vertically through the center ports into an overlying chamber and finally in reversed right and left hand directions to both 75 sides of an upper chamber.

2. In an electric furnace for distilling spelter having right and left hand condensers, a ported septum through which the hot fume passes into direct contact with the 80 longitudinal center of the roof, the rate of heat radiation from the roof being controllable, whereby the temperature of the fume is reduced prior to entering the condensers.

3. An electric zinc furnace for distilling spelter having an attached condenser, or condensers, adapted to receive zinc-fume from a chamber formed by a ported septum and an overlying roof, the rate of heat radiation 90 from said roof being controllable, whereby the temperature of the hot fume from the ported septum is reduced, by contact with the roof, prior to entering the condenser.

This specification signed and witnessed 95 this 26th day of January, A. D. 1916.

JOHN THOMSON.
